UNITED STATES PATENT OFFICE.

EMIL F. HAFELFINGER, OF WEEHAWKEN, NEW JERSEY.

EXHAUST DEVICE FOR COMPRESSION-ENGINES.

No. 905,870.

Specification of Letters Patent.

Patented Dec. 8, 1908.

Application filed August 29, 1906. Serial No. 332,434.

To all whom it may concern:

Be it known that I, EMIL F. HAFELFINGER, a citizen of the United States of America, residing at Weehawken, in the county of Hudson and State of New Jersey, have invented a new and useful Exhaust Device for Compression-Engines; and I do hereby declare the following to be a full, clear, and exact description of the same.

- 10 My present invention relates especially to novel means whereby an exhaust valve of a gas or gasoline engine is opened, to the extent desired, during the starting of the motor. At such time, especially when the motor is used to drive a motor-bicycle or an automobile, it is especially desirable to lift the exhaust valve stem, in order that the normal compression be relieved as the engine is started.
- 15 In the accompanying drawing, I have shown a form of arrangement which is especially useful in connection with a motor-bicycle (one driven by a hydrocarbon motor, preferably), and, for convenience and 20 economy in construction, have also shown the lifter controlling device combined with a rod or the like which controls the sparking means.

Referring to the drawings, Figure 1 shows, somewhat diagrammatically, my improvements as applied to a motor-bicycle, part of the frame being shown; Fig. 2 shows (enlarged) the relations of the parts during starting of the engine; and Fig. 3 is an end 35 view of the assembled valve-lifter, lever therefor, cam and lever-controller, all removed from the casing.

1 indicates the bottom front-brace of a bicycle-frame, and 2 indicates a chain for 40 driving the rear-sprocket.

3 indicates the fly-wheel case, and 4 indicates the engine cylinder, wherein a mixture of vaporized gasoline with compressed air is ignited.

45 5 indicates a casing for containing an exhaust valve, and 6 indicates the stem of such a valve. A spring, 7, surrounding said valve, yieldingly holds it to place.

8 indicates a pipe through which is fed 50 gasoline from a carburetor.

The device is provided with a valve lifter, 10, and I have shown a vertical rod for said purpose, said rod slidably fitting within a bore formed through an extension 95 of the 55 cam-casing 11. Said casing 11 is in the form of a shell or cap, secured by screws 75

to the fly-wheel case, 3, and is provided with a bottom ring which fits the fly-wheel axle 40. Near its bottom end, said cam-casing is bored diagonally through its opposite side 60 walls, and a bolt 12 is slidably fitted within the bores thus formed, and normally the lower end of said bolt yieldingly projects, as shown in Fig. 1, a slight distance from the casing. For this purpose, the opposite ends 65 of a spring 27 fit in a recess in the upper end of bolt 12 and in a recess 25 in a screw cap 26, the threads of which engage with threads of the bore 14 of the casing, and which is used to adjust the tension of spring 70 27 or to remove same.

15 indicates a cam or projection carried by a spark-controller or sparker (shown dotted at 16), and such cam or projection may, as shown in the drawings, be carried 75 by a plate 17, (oscillating upon the outside of the cam-casing) movable to valve-lifting position (as shown in Fig. 2) or to a position ineffective upon the valve (as shown in Fig. 1), by means of a rod 18, one end of 80 which is connected with the plate 17 and the other end of which is connected with any desired point upon the motor-bicycle, such as a small lever pivotally carried by the top-bar of the bicycle-frame.

85 In the position shown in Fig. 1, the cam 15 is drawn away from the end of the bolt 12, and such bolt projects from the casing 11. This downward projection of the bolt draws the valve lifter down to a position where 90 it will be operated, at the desired regular intervals, by an exhaust valve cam. In such position, as shown in Fig. 1, the upper end of the valve lifter 10 is slightly separated from the lower end of the exhaust valve 95 stem 6, so as to permit independent adjustment of the latter.

The bolt 12 is employed to positively raise and lower the valve-lifter 10, so as to be maintained open or partly open, or be 100 regularly acted upon by the exhaust valve cam. For this purpose (see Figs. 2 and 3), the bolt 12 is provided with an inwardly-projecting pin 28, and such pin projects through the slot 29 in the lower arm of a 105 lever 30 within the cam-casing 11 and pivoted at 31. The upper arm 32 of such lever slidably engages with the lower end 34 of the valve-lifter 10, and underneath a shoulder 33 as provided by cutting away a portion of such valve-lifter.

In the normal position of the parts (the

running position shown in Fig. 1) the disengagement of cam 15 from the bolt, permits projection of the latter, and causes the upper arm 32 of the lever to be drawn downwardly, and the valve-lifter 10 to be moved downwardly in its casing by the spring 7, acting upon the stem 6. In such position, the lower end 34 of the lifter will be in the path of the exhaust-valve cam 51, driven by shaft 50, and the lifter will be regularly raised and lowered once for each rotation of the shaft 50, and will effect the exhaust as desired. When, however, the bicycle has been stopped, and it is desired to again start the motor, it is usual for the rider to do so by pedaling a few strokes until the motor begins to regularly operate, and it is advisable to have the normal compression of the engine relieved until such regular operation of the motor is assured. For this purpose, the sparker or plate 17 is drawn forward (as shown in Fig. 2) by means of the rod 18 and the engagement of the came 15 of such plate with the bolt causes the retreat of the latter and the movement of the lever 30 to the position shown in Fig. 2, whereupon the upper arm 32 of such lever pushes the valve lifter 10 and the latter holds the exhaust valve from its seat, and permits the compression to be relieved until the rod 18 and plate 17 are operated as desired. It will be readily understood, of course, that the degree of projection and (by means of the lever 30) the extent of opening of the exhaust valve may be varied as desired, and may also be changed during the running of the motor-bicycle or other vehicle, by causing the cam 15 to engage with the bolt 12 to any extent desired.

The form of my invention illustrated in the drawings, is one which permits a ready and easy control of the exhaust of the motor especially during the starting, and is simple, durable and economical. In addition, the employment of my invention, especially when using a cam controlled by a spark-controller or sparker, results in a reduction

of the number of operating parts and a lessening of care necessary to be given to the machine.

What I claim is:

1. In an exhaust device for explosion engines, an exhaust-valve lifter, an exhaust-valve cam, and means comprising a bolt and a cam for moving said bolt as desired, for moving the exhaust-valve lifter into and out of the path of the exhaust-valve cam.

2. In an exhaust device for explosion engines, an exhaust-valve cam casing, an exhaust-valve lifter mounted for reciprocation in said casing, a lever pivoted within the casing and having an arm in engagement with the exhaust-valve lifter, a bolt slidably mounted in the casing and engaging the lever, and means for moving the bolt as desired.

3. In an exhaust device for explosion engines, an exhaust-valve lifter, an exhaust-valve cam, and a bolt and connections therefrom for moving said exhaust-valve lifter into and out of the path of said cam, in combination with a pivoted plate provided with a cam and arranged to operate the bolt aforesaid.

4. In an explosion engine, the combination of an exhaust valve stem, a lifter therefor, a pivoted lever which engages said lifter, a longitudinally movable bolt adapted to move said lever, an adjustable ignition mechanism, means attached to said ignition mechanism, adapted to engage said bolt, means for holding said bolt in contact with said last mentioned means, an adjusting means attached to said ignition mechanism, said parts being arranged for a simultaneous adjustment of the ignition mechanism and valve stem.

In testimony whereof, I have signed my name to this specification in the presence of two subscribing witnesses.

EMIL F. HAFELFINGER.
